US00D664392S

(12) **United States Design Patent**
Enghard

(10) **Patent No.:** **US D664,392 S**
(45) **Date of Patent:** **** Jul. 31, 2012**

(54) **MIXING ELEMENT FOR A BEVERAGE SHAKER**

(76) Inventor: **Florian Enghard**, Sulzbach (DE)

(**) Term: **14 Years**

(21) Appl. No.: **29/393,879**

(22) Filed: **Jun. 10, 2011**

(30) **Foreign Application Priority Data**

Dec. 11, 2010 (DE) 40 2010 006 605

Primary Examiner — Ricky Pham

(74) *Attorney, Agent, or Firm* — W. F. Fasse

(57) **CLAIM**

The ornamental design for a mixing element for a beverage shaker, as shown and described.

DESCRIPTION

FIG. 1 is a top front right perspective view of a mixing element for a beverage shaker showing my new design.

FIG. 2 is a top plan view thereof.

FIG. 3 is a right side elevation view thereof.

FIG. 4 is a front elevation view thereof.

FIG. 5 is a bottom plan view thereof.

FIG. 6 is a left side elevation view thereof; and,

FIG. 7 is a back elevation view thereof.
